UNITED STATES PATENT OFFICE.

SHUBLE Y. SEEDS, OF OKLAHOMA, OKLAHOMA.

WASHING MACHINE.

Application filed May 8, 1921. Serial No. 468,038.

To all whom it may concern:

Be it known that I, SHUBLE Y. SEEDS, a citizen of the United States, and a resident of Oklahoma city, in the county of Oklahoma and State of Oklahoma, have invented certain Improvements in Washing Machines, of which the following is a specification, reference being had to the accompanying drawings.

10 An object of the invention is to provide a machine for washing clothes and other fabric articles.

Other objects and advantages of the invention will be set forth in the ensuing description.

Figure 1 of the drawings is a side elevation of the improved machine.

Figure 2 is a horizontal sectional view taken on the line 2—2 of Figure 1.

20 Figure 3 is a similar view taken on the line 3—3 of Figure 1.

Figure 4 is a sectional view taken on the line 4—4 of Figure 1.

Like characters of reference designate like parts in all the figures.

25 The improved machine includes a rectangular sheet-metal container 5 for water and the articles 6 to be washed, this container being provided at each of its four corners with legs 7.

30 The container 5 is divided into two compartments 8 by a vertical cross wall 9, and the lower edge of this wall is spaced a short distance from the bottom 10 of the container 35 so that the water may pass under it from one compartment to the other.

35 The container 5 is provided with two lids 11 which are connected to the upper edges of the side walls 12 by hinges 13, these lids 40 meeting each other on a central longitudinal line as best shown in Figure 3.

45 Each of the two compartments 8 is provided with a close-fitting plunger 14, and each plunger is provided with a central vertical controlling stem 15.

The lids 11 are cut away as at 16 to loosely clear the stems 15 of the plungers 14.

50 To support other parts of the machine, a pressed-metal standard 17 is riveted to each end wall 18 of the container 5, the two standards being structurally connected at about mid height by a horizontal wooden member 19 which is provided with notches 20 to receive and guide the stems 15 of the 55 plungers 14.

The ends of the wooden member 19 are bolted to brackets 21 and 22 which are in turn riveted to the standards 17.

To removably hold the stems 15 in the guiding notches 20 of the member 19, a retaining bar 23 is arranged to be swung to and from holding position in a horizontal plane, one end of this bar being bent downward to form a vertical pivot-pin 24 which extends down revolvably through bearings 25 on the bracket 22.

This bar 23 is provided with rollers 26 which revolve around it and co-operate with the wooden member 19 in guiding the vertical movements of the stems 15, these rollers 27 being held against endwise movement on the bar by tight collars 28.

In closing the bar 23 to holding position, its free end 28 is forced over and behind a holding lip 29 on the bracket 21.

75 To impart vertical reciprocating movement to the stems 15 and plungers 14, a crank-shaft 30 is journaled in bearings 31 on the upper ends of the standards 17, and connecting-rods 32 operatively connect the 80 cranks 33 of said crank-shaft to the upper ends of the stems 15.

The crank-shaft 30 is provided with a crank 34 for manually driving it; and the two cranks 33 are diametrically opposed to 85 produce an alternating movement of the plungers 14.

Each connecting-rod 32 includes two sections 32^b and 32^c which telescope for adjustment of their length, and the two sections are 90 locked in adjusted position by pins 35 which pass through them.

Near the bottom 10 of each compartment 8 a screen 36 is supported in a horizontal plane by ledges 37 which are secured to the walls 95 12 and 18 and to the lower edge of the cross wall 9.

In preparing to operate the machine, the clothes or other articles 6 to be washed are placed in the two compartments 8, where 100 they rest on the screens 36 or float in the water.

As each plunger moves downward in its respective compartment 8 under action of the crank-shaft 30 it forces the water in said 105 compartment down through its respective screen 36, thereby forcing the articles 6 down onto said screen and driving the water through them.

The water thus forced down through the 110

screen 36 and articles 6 passes under the cross wall 9 and up through the screen 36 of the other compartment 8 under the ascending plunger 14 of said compartment, thus 5 raising the articles 6 off of said screen and changing them in position for a following down stroke of said plunger.

When the washing has been finished, the connecting-rods 32 may be disengaged from 10 the stems 15 by removing the pins 38, and the lids 11 may be opened.

Then, by swinging the bar 23 away from the stems 15 the plungers 14 may be removed.

15 A clean-out pipe 39 may be provided for the container 5, and said pipe may be provided with a suitable valve 40.

The following is claimed:—

In a washing machine, a container for water, a plunger in the container and having 20 an upstanding stem, supporting standards carried by the container, a structural member connecting the standards and adapted to guide the movements of the stem, a bar pivoted to one of the standards and arranged to 25 swing in a horizontal plane, said bar being adapted to co-act with the structural member in guiding the stem, a roller carried revolvably on the bar to engage the stem, and means for locking the free end of the bar 30 against movement.

Witness my hand this 30 day of April, 1921.

SHUBLE Y. SEEDS.
